(57) **CLAIM**

The ornamental design for a surveillance camera as shown and described.

DESCRIPTION

FIG. 1 is a front, right-side, bottom perspective view of a surveillance camera, showing the new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof; and,
FIG. 8 is a rear, right-side, top perspective view thereof.
The broken lines depict parts of the surveillance camera that form no part of the claimed design.

1 Claim, 8 Drawing Sheets
